(57) **CLAIM**

The ornamental design for an integration management system for patient table, as shown and described.

DESCRIPTION

FIG. 1 is a front perspective view of a design for an integration management system for patient table according to the present invention with an upper table compartment according to the present invention.

FIG. 2 is a back perspective view of the integration management system for patient table of FIG. 1.

FIG. 3 is a top view of the integration management system for patient table of FIG. 1.

FIG. 4 is a right side view of the integration management system for patient table of FIG. 1.

FIG. 5 is a left side view of the integration management system for patient table of FIG. 1.

FIG. 6 is a back view of the integration management system for patient table of FIG. 1.

FIG. 7 is a front view of the integration management system for patient table of FIG. 1.

FIG. 8 is a bottom view of the integration management system for patient table of FIG. 1.

FIG. 9 is a front perspective view of the integration management system for patient table of FIG. 1 with the upper table compartment in a first open configuration.

FIG. 10 is a front perspective view of the integration management system for patient table of FIG. 1 with the upper table compartment in a second open configuration; and,

FIG. 11 is a back perspective view of the integration management system for patient table of FIG. 1 with the upper table compartment in a third open configuration.

The broken lines immediately adjacent the shaded areas represent the bounds of the claim, while all other broken lines are directed to environment and are for illustrative purposes only. The broken lines form no part of the claimed design.
